CLAIM

The ornamental design for a display screen or portion thereof with a graphical user interface for a home buying idea board as shown and described.

DESCRIPTION

The FIGURE is a front view of a display screen or portion thereof with a user interface for a home buying idea board. The outer perimeter broken lines in the FIGURE depict a display screen or portion thereof and form no part of the claimed design. The remaining broken lines in the FIGURE depict portions of a graphical user interface for a home buying idea board and form no part of the claimed design.

1 Claim, 1 Drawing Sheet
